United States Patent Office

Des. 188,363
Patented July 5, 1960

188,363

BARRETTE

Irene M. Dorr, 103 Oakway Road, Timonium, Md.

Filed June 29, 1959, Ser. No. 56,572

Term of patent 14 years

(Cl. D86—8)

Fig. 1 is a perspective view of a barrette showing my new design as it appears in open position;

Fig. 2 is an enlarged side elevational view thereof as it appears in closed position;

Fig. 3 is a plan view thereof; and

Fig. 4 is a cross section taken along line 4—4 of Fig. 2.

I claim:

The ornamental design for a barrette, as shown.
